UNITED STATES PATENT OFFICE.

SAMUEL TULLY WILLSON, OF NEW YORK, N. Y.

VAT-DRIER.

1,150,920.

Specification of Letters Patent. Patented Aug. 24, 1915.

Application filed September 21, 1914 Serial No. 362,826.

To all whom it may concern:

Be it known that I, SAMUEL TULLY WILLSON, a citizen of the United States of America, and a resident of the borough of Brooklyn of the city of New York, in the county of Kings and State of New York, have invented certain new and useful Improvements in Vat-Driers, of which the following is a specification.

10 This invention relates to heating devices and especially to that class of heaters, used for drying vats, such as are used in breweries.

The object of the invention is to provide 15 a device which is portable, which may be introduced into a vat through the usual man hole, in which complete combustion takes place, in which combustion is entirely independent of the air within the vat. In 20 which fluid fuel is used. The fluid fuel and air for combustion being conveyed to the heater from the outside. Complete control of combustion being possible without entering the vat during the heating process.

25 With these and other objects in view, the invention comprises new and novel constructions, combinations and arrangements of parts, as will be hereinafter more fully described and claimed.

30 In the drawings:—Figure 1 is a transverse section through A B of Fig. 2. Fig. 2 is an outside elevation showing my improved vat drier together with flexible metal tube, through which fluid fuel and air are supplied to the heater and also the fuel and air cocks by which their proportions are controlled.

Like characters of reference designate corresponding parts throughout both views.

40 In its preferred embodiment the improved heater forming the subject matter of this application, comprises a hexagonal body in two parts, the top part 1, and the bottom part 2. The two parts are bolted together 45 as at 3 forming a combustion chamber which is entirely inclosed except for openings 4 which occur at each end. The door 5 is supplied to facilitate lighting the burner 6 which may be arranged to burn various 50 kinds of fluid fuels. The fluid fuel and air are supplied through a flexible tube 7 with valve 8 to control the air supply and an offset cock 9 to control the fluid fuel supply.

Either the air or fluid fuel being under sufficient pressure to force both through the 55 burner.

For facility in handling and placing the heater within the vat, which may have a small aperture, the heater body is free from a carriage, which not only acts as a support 60 for the heater body; but is supplied with rollers 11, which facilitates moving it to a central position on the floor of the vat, after the burner has been lighted at a convenient location near the man hole, through which 65 the heater is introduced into the vat. The carriage has a body 10 supplied with a baffle 12 intermediate of its top and bottom to prevent an excess of heat striking the floor 70 of the vat.

In operating this device the carriage is first introduced through the man hole. The heater is then introduced and placed upon the carriage, the burner is then lighted through the door 5 and proper adjustment 75 of fuel and air made. The carriage with the heater in place is then rolled by aid of the flexible tube which is somewhat stiff or by use of a rod to a position near the center of the vat. The proper adjustment of the 80 burner is easily determined by observation of the flame issuing from the openings 4 in the ends of the heater.

The burner 6 forms a support for the heater body 10 along one side thereof and rests 85 freely in a curved seat on the carriage while the other side of the heater body 10 is provided with supports which rest freely in a curved seat at the other side of the carriage and are engaged therewith by depending 90 lugs which prevent the heater body from moving endwise of the carriage when the latter is placed thereon. The burner being located at one side of the heater body the flames issuing therefrom sweep around the 95 interior of the heater body from one side to the other side thereof. The heater body being detachable, a carriage and heater body, each of about the dimensions of the man hole, may be employed.

Having thus described my invention the following is what I claim as new therein and desire to secure by Letters Patent:

1. A vat drier comprising a heater body, a burner located and providing a support 105 at one side of the heater body, supports

located at the other side of the heater body, and a tube connected with the burner having air supply and fluid fuel valves, the location of the burner at one side of the heater causing the flames issuing therefrom to sweep upwardly from one side around the interior of the heater body.

2. A vat drier comprising a hexagonal heater body, a burner located and providing a support at one side of the heater body, supports located at the other side of the heater body and a tube connected with the burner having air supply and fluid fuel valves.

15 3. A vat drier comprising a heater body formed with a bottom part, a top part detachable from the bottom part, a burner located and providing a support at one side of the bottom part, supports located at the other side of the bottom part and a tube connected with the burner having air supply and fluid fuel valves.

4. A vat drier comprising a carriage having curved seats one at each side thereof and a heater body having side supports whereby it is detachably mounted on said curved seats and spaced from the carriage.

25 5. A vat drier comprising a carriage having a curved seat at each side thereof and 30 a heater body having a burner occupying

one curved seat and supports occupying the other curved seat.

6. A vat drier comprising a heater body and a carriage for supporting the heater body having a baffle plate intermediate of the top and bottom thereof.

7. A vat drier comprising a carriage constructed to support a heater body, a heater body separable from said carriage, supports between the carriage and heater body for supporting said heater body upon and spaced from the carriage, a fuel burner mounted in the heater body, and a fuel supply tube connected with the burner.

8. A vat drier comprising a wheeled carriage constructed to support a heater body, a heater body separable from said carriage, supports between the carriage and heater body for supporting said heater body upon and spaced from the carriage, a fuel burner mounted in the heater body, and a fuel supply tube connected with the burner.

Signed at New York, borough of Brooklyn, in the county of Kings and State of New York this 18th day of September A.D. 55
1914.

SAMUEL TULLY WILLSON.
